(57) **CLAIM**

The ornamental design for a shoe sock, as shown and described.

DESCRIPTION

The present invention is a shoe sock, having a rounded edge, for use in covering an inner portion of a shoe.

FIG. 1 is a perspective view of a shoe sock.

FIG. 2 is a top view of the shoe sock.

FIG. 3 is a left side elevational view of the shoe sock.

FIG. 4 is a right side elevational view of the shoe sock.

FIG. 5 is a front perspective view of the shoe sock.

FIG. 6 is a rear perspective view of the shoe sock; and,

FIG. 7 is a sectional view along line 7—7 of FIG. 2.
